UNITED STATES PATENT OFFICE.

DENIS M. BECK, OF CINCINNATI, OHIO.

LIFT-CUTTING AND HEEL-BUILDING APPARATUS.

SPECIFICATION forming part of Letters Patent No. 728,658, dated May 19, 1903.

Application filed July 2, 1902. Serial No. 114,037. (No model.)

To all whom it may concern:

Be it known that I, DENIS M. BECK, a citizen of the United States, residing at Cincinnati, in the county of Hamilton and State of Ohio, have made certain new and useful Improvements in Lift-Cutting and Heel-Building Apparatus, of which the following is a specification.

By the usual method of forming heels of boots and shoes the lifts are first cut out and then built up in proper form. This requires the services of two workmen. In the building-up process the workman picks up the lifts singly and applies glue or some other cement so they duly adhere in the completed heel. In the use of my apparatus the lifts are cut out and built up into a heel at one operation, and this is attended with the additional advantage that there is no danger of producing a faulty or defective heel by a failure to apply the glue. The lifts are cut out of a piece of leather to which glue has been first applied. The lifts are so cut and arranged in the die and are so secured together while so retained therein that it is impossible that the heel finally produced shall be other than perfect in form. In other words, the lifts all assume the same proper position relative to the die and to each other as they are successively cut and received into the die. Thus the common defect of imperfect heels—that is to say, heels which are irregular in form—and also the frequent occurrence of cracks in the heels due to imperfect gluing are avoided.

In carrying out my invention I employ a series of cutting - dies having, however, the same form and construction and differing only in size. For such dies I provide a detachable head or anvil, upon which blows are delivered by a mallet for the purpose of forcing the die into and through the leather. In connection with such die-head I employ an attachment which is adapted to perform two important functions—namely, to drive a nail through the several lifts held in the die and then to eject the lifts from the die. Such attachment is adapted to slide vertically upon and be guided by the die-head. The latter is provided with awls or piercing-points for successively taking up the lifts cut by the die, to which the head is attached. The die is adapted to be placed and supported in a

holder, which is provided with a slidable plate that serves to support the heel-lifts while a nail is driven through them, it being then retracted to allow the lifts to be ejected from the die.

The details of construction, arrangement, combination, and operation of parts comprising my apparatus are as hereinafter described, reference being had to accompanying drawings, (three sheets), in which—

Figure 1 is a perspective view of the entire apparatus, certain parts—to wit, the die-head and the nail-driving and lift-ejecting attachment—being, however, shown detached from each other and from the die. Fig. 2 is a side view of the apparatus. Fig. 3 is a central vertical longitudinal section of the apparatus, the nail-driving and heel-ejecting device being shown in the position it reaches when the lifts have been forced off the awls, forming an attachment of the die-head. Fig. 4 is a perspective view of one of the cutting-dies. Fig. 5 is a bottom plan view of the die-head or anvil attachment for the die. Fig. 6 is a bottom plan view of the head of the nail-driving and lift-ejecting attachment. Fig. 7 is an end view of the apparatus. Fig. 8 is a central vertical transverse section of the apparatus, the section being at right angles to that shown in Fig. 3 and the nail-driving attachment being shown in the position it attains when the nail is driven part way into the heel-lifts. Fig. 9 is a sectional view showing the die and its head or anvil attachment and illustrating the operation of cutting out lifts from a sheet or piece of leather. Fig. 10 is a side view of the same parts—to wit, the die and die-head. Fig. 11 is a perspective view of that portion of the apparatus which is secured upon a bed or table, the same illustrating particularly the sliding support for the heel-lifts when a nail is being driven through the lifts. Fig. 12 is a perspective view of one of the lift-ejectors proper.

Referring in the first instance to Fig. 1, X indicates a stationary horizontal bench or table upon which the stationary portion of my improved apparatus is duly secured. As indicated in Figs. 3 and 8, the said bench or table X is provided with an opening directly below the main frame F of my apparatus.

The chief parts of my apparatus are a cut-

ting-die A, a die-head or anvil attachment B, and a nail-driving and lift-ejecting device C. In Fig. 1 the parts B and C are shown disassociated or separated from each other and from the die A. The die-head B is, however, employed with the die proper, A, in cutting out lifts, as illustrated in Fig. 9, while Y indicates a leather plate or piece, and Z' a series of lifts already cut out and inclosed by the die. As shown best in Fig. 4, the steel die is constructed hollow and with a duly-beveled or sharp cutting edge. In practice the chamber of the die is slightly enlarged from the cutting edge upward, so that the lifts will pass easily up into the same. The die is shown provided with four cut-outs or notches a in its upper edge. These are for the reception of the cruciform base portion or anvil portion of the die-head B—that is to say, the die-head is provided with four arms b' b' , projecting at right angles to each other and forming a fixed attachment of the cylindrical vertical portion b . These arms transmit to the die A the pressure caused by blows of a mallet delivered on the vertical central portion b . The die A and die-head B are detachably connected when used together by means of spring-catches, whose construction and arrangement are as follows: As shown best in Fig. 3, the catches are T shape, the horizontal and vertical portions working in cavities or recesses in the under side of the smaller arms b' of the die-head. Push-pins b^4 are adapted to slide in bores formed in such arms b' and are suitably attached to the vertical portions of the catches b^3 . Spiral springs b^5 are arranged behind the vertical portions of the catches, so that the latter are normally held projected, as shown. The catches b^3 enter slots a^2 (see Fig. 4) in the die A. In order to detach the die-head B from the die A, the thumb and finger are applied to the push-pins b^4 , so that the springs b^5 are compressed and the notches pushed inward out of engagement with the slots a^2 of the die, as will be readily understood. By this construction and arrangement of parts the die-head may be very easily and quickly applied to and detached from a die.

To the underside of the die-head proper, B, is applied a series of metal plates b^2 . (See especially Figs. 3, 5, and 9.) These plates are secured by screws, and their number may be increased or diminished at will as required, according to the thickness the completed heel is to have. Awls or piercing-points b^6 are secured by these plates, as best shown in Fig. 3—that is to say, the said awls have enlarged heads and pass through the outer plate b^2 , and thus project downward parallel. They may be, however, secured in any other suitable manner, so that they form a rigid attachment of the die-head and are adapted to pierce the lifts Z', and thus serve as pickups for the latter.

I provide the die-head B with a means for indicating the number of lifts, or rather the

aggregate thickness of the several lifts, that have been picked up. The same consists of a slidable rod b^8 , (see Figs. 8 and 9,) which passes down through a vertical bore in the base portion of the die-head B and is provided with a laterally-projecting head which works in a vertical guide-slot b^9 in the vertical portion b of the die-head. A slotted graduated plate b^{10} is applied to the part b of the die-head. It will be seen that the head or lateral projection of the rod b^8 slides over the graduations on the plate b^{10} . A spiral spring b^{11} (see Fig. 8) is arranged above the rod b^8 , so that the latter is held normally pressed downward. It will be apparent that in the operation of cutting out lifts, as shown in Fig. 9, this rod b^8 is pushed upward by the lifts Z' as they enter the die, and as the rod is pushed upward the greater will be the number or thickness of the lifts. The graduation on the plate b^{10} is such as required to indicate the thickness of the lifts in a particular manner—that is to say, for a seven-eighths-inch heel the indicator or gage-rod b^8 will point to "7," which would indicate the die was full and the heel completed. The graduations will be one-eighth of an inch and one-sixteenth of an inch, as on an ordinary rule.

It will be understood that when a sufficient number of lifts Z' have been cut out and received into the die A the latter, together with the die-head locked thereto, is transmitted to the holder B. This is a thick plate having a socket exactly conforming to the shape and size of the lower portion of the die A. The said plate D is secured by screws upon the upper side of the horizontal frame F, which, as before indicated, is duly secured upon the bench or table X. In order to support the die in the required position, (see Fig. 1,) the die is provided with lateral lugs or projections A', which rest upon the upper side and edge of the plate D. Having now placed the die A and die-head B in due position, as indicated in Figs. 2, 3, 7, and 8, the next operation is to drive a nail through the several lifts, so that they may be secured together before being ejected from the die. The die-head B is provided with a central vertical bore b^{12} . (See Figs. 1 and 8.) Into this bore a nail Z is dropped. The nail-driving device C is then applied. As shown best in Fig. 1, this consists of the following parts, to wit: an anvil or head-block c, four parallel pendent arms c', that serve as lift-ejectors, and a central pendent pusher or hammer rod c². The latter is adapted to enter the bore b^{12} in the die-head B and to pass through the same. As shown in Fig. 8, this hammer-rod c² has been forced down far enough to drive the nail Z part way through the assembled lifts Z', which are supported upon a plate E, adapted to slide in the frame F, as will be presently described. In order to thus force the nail into and through the lifts Z', blows are delivered by means of a mallet or hammer upon the thick anvil or

head *c* of the device *C*. For the purpose of turning the point of the nail *Z* upon the under side of the lifts, so as to duly secure the latter together, I provide the slide *E* with a 5 steel plate *e*. (See Figs. 8 and 11.) I likewise provide the said plate *E* with wooden filling-pieces *e'*, so that the edge of the die *A* may not be injured by contact therewith. The lifts having been thus nailed together, 10 the next step is their ejection from the die. This is effected by the four pushers or rods *c'*. As will be understood by reference to Figs. 1, 2, 3, 7, and 8, these rods *c'* are so placed as to pass down on the sides of and in 15 contact with the cylindrical vertical portion of the die-head *B* and to pass farther down in the angles between the arms *b'* and *b''* of the die-head and still farther through holes *b'''* in the metal plates *b''*, which are secured 20 to the cruciform base of the die-head. As illustrated in Fig. 3, the pushers *c'* are of such length that when the anvil or head *c* of the ejectors *C* strikes upon the cylindrical vertical portion *b* of the die-head *B* the said pushers project beyond the bottom of the die-head 25 far enough to completely eject the lifts previously held in the die *A*. In other words, the lower ends of the pushers *c'* are of such length that they will project nearly to the lower 30 edge of the die *A*. It is apparent that, following the nail operation before described, the ejector *C* is simply driven farther down by blows delivered upon the head *c*, so that from the position indicated in Figs. 7 and 8 35 the position indicated in Figs. 2 and 3 is assumed, or, in other words, the device *c* is forced down to its lowest limit of movement. It is apparent that in such operation the die-head *B* serves as a means for guiding and 40 steadyng the device *C*. In order to break the shock incident to delivering blows upon the head *c* of the device *C*, I provide the latter with an elastic or rubber block *c''*, (see Figs. 3 and 6,) the same being secured by 45 means of screws in the space between the pushers or lift-ejectors proper, *c'*. The latter are preferably secured to the head *c'* by screwing them into sockets in the latter. They also pass through holes formed in a metal 50 plate *c''*, which is suitably secured to the head *c* and is interposed between the head proper and the rubber plate *c''*.

The plate *E*, before referred to, slides in guide grooves or ways *f*, provided in the opposite sides of the fixed frame *F*. Springs *e''* (see Figs. 3 and 11) serve to hold the plate *E* shoved forward in its normal working position. (Indicated by dotted lines in Fig. 2.) The said springs *e''* are formed of two wires 60 bent or coiled upon themselves and secured at one end to the frame *F*, their free ends projecting upward and working in contact with the outer edge or end of the plate *E*. For the purpose of retracting the plate *E* 65 against the tension of the springs *e''* I employ a treadle *G*, (see Fig. 1,) which is connected by a cord *e'''* with a rear projection of the plate

E. The said cord *e'''* passes over a pulley *e''*, which is arranged upon the rear portion of the frame *F*. (See Figs. 1 and 3.) It will be 70 seen that in its forward movement the front end of the plate *E* comes in contact with the head *f'* of the frame *F*. The said head *f'* is preferably formed of a metal plate, which is 75 screwed to the frame proper, *F*.

I will now briefly describe the operation of my improved apparatus as a whole. It will be understood that the preparatory step consists in applying glue to the leather plate *Y*, from which the heel-lifts are to be cut by the 80 die. It is important that the glue shall be of the best quality and that it be applied to the flesh side of the leather. Where time permits, it is left to dry perfectly on the leather before the latter is cut, and in such case immediately before the cutting operation is begun the grain side of the leather requires to be slightly moistened with water. When time does not permit the glue to dry and the leather is to be cut immediately after its 85 application, the glue is to be applied to the grain side of the leather, since the glue does not become hardened and the lifts will adhere without additional moisture. In cold weather the glue will thicken somewhat; but it may 90 be kept warm or a little nitric acid may be added to keep it in a duly fluid condition. The latter being properly glued, as indicated, the several lifts cut therefrom will adhere to each other with great tenacity, so as to form a 95 practically homogeneous or solid heel without cracks, which frequently occur in handmade heels owing to failure of the workman to properly apply glue thereto. As has been already indicated, the die-head *B* is first secured to the die proper, *A*, by means of the catches or locking devices *b''*. The die *A* is then set upon the leather piece *Y*, (see Fig. 9,) and blows are delivered upon the anvil *b* of the die-head, so as to force the cutting edge 100 of the die into and through the leather. The lift thus formed is pierced by the awls or points *b''*, whose lower ends are on the same level with the edge of the die. The said awls thus pick up the severed lift and hold it 105 within the die. This operation is repeated until as many lifts have been cut and taken up into the die as may be necessary to make a heel of the desired thickness. It must here be stated that while a single die *A* has been 110 illustrated and so far described in practice I employ a series of dies owing to the tapered form of a boot or shoe heel. It will be understood that these dies are duplicates of each other in respect to form and differ only in 115 respect to size, and since the lowest lift of a heel is the smallest it is obvious that the first die employed will be the smallest of the series. The second die or the one used after the first one will be slightly larger. The die-head *B* is therefore detached from the first die and applied to the second or larger die. It will be understood that this operation is 120 effected by pressing inward the push-bar *b''*, 125

so that the springs b^5 (see Fig. 3) are compressed and the catches b^8 thereby released from engagement with the die. The die-head is then set upon the second die and springs 5 compressed, as before, and then allowed to expand, so that the catches enter the slots a^2 thereof and lock the die-head to such die. With such second die as many lifts of the second size are cut as required. The work- 10 man continues the operation by applying the die-head B to a third die of larger size than the second die, and so on, using as many different dies as the taper and length of the heel may require. It will be understood that 15 in each case the awls b^6 hold and carry with the die-head B all the lifts that have been cut by the several dies. Thus by using larger dies successively a series of lifts are finally accumulated in the last die, and the work- 20 man knows when a sufficient number of lifts or a sufficient thickness of the series of lifts has been cut by observing the indicator b^8 —that is to say, by observing the height to which the gage-rod b^8 has been forced upward, the 25 distance being indicated by means of the graduations on the slotted plate b^{10} . The last die used is the one which is to be placed in the holder D, and the preliminary or first position of parts is sufficiently indicated in Figs. 7 and 30 8—that is to say, the last die A is set into the holder D with the die-head B secured thereto. The nail-driving and lift-ejecting device C is then applied, as indicated, the nail Z having been first dropped through the bore 35 b^{12} in the die-head. Blows are then applied by means of a mallet to the head c of the nail-driving device C, whereby the elongated nail hammer or rod c^2 forces the nail Z through the bore b^{12} into the pile of lifts Z'. In Fig. 40 8 the nail, as indicated, is driven part way through. It is apparent that if the device C be forced down far enough to drive the nail Z completely through the lifts the point of the nail will strike upon the steel plate or anvil 45 e, which rests in the center of the sliding plate E, and be thereby turned and clenched, so as to hold the lifts secured firmly together to form practically a solid leather block having the form and size of the required heel. 50 It is further apparent that when the nail hammer c^2 has thus forced the nail through the lifts the ejectors or pushers c' of the device c will come in contact with the lifts Z' and by forcing said device down to the position indicated in Figs. 2 and 3 the assembled 55 lifts will be forced out of the die. It will be understood, however, that before this operation can be effected the plate E must be slid back from beneath the die. For this purpose 60 the operator places his foot upon the treadle G, Fig. 1, and by depressing the same draws the plate E back against the tension of the springs e^4 and into the position indicated in Fig. 3. This leaves the space or opening in 65 the frame F free, so that the lifts ejected from the dies fall through the same and through the coincident opening in the bench

or table X into a receptacle. (Not shown.) In brief the depression of the treadle G must occur immediately following the driving of the 70 nail and before the device C is forced down to bring the pushers c' into contact with the lifts. The operator now lifts the empty die and its attached parts B and C out of the holder D and removes his foot from the treadle 75 to allow the slide E to assume its former position ready for the driving of a nail into the next series of lifts that may be cut. He then detaches the device C from the die-head B and in turn releases the latter from the empty 80 die and reattaches it to the smallest die of the series with which he begins the next lift-cutting operation.

It will be noted that the points of the awls are slightly curved, or bent laterally. This 85 is for the purpose of enabling them to take a firm hold in the lifts, and thus raise them as well as hold them in the die until forcibly ejected.

Having thus described my invention, what 90 I claim as new, and desire to secure by Letters Patent, is—

1. The combination, with the lift-cutting die, of the anvil attachment comprising the radial base portion and a vertical portion rising 95 centrally therefrom, the two parts engaging at the point of contact so as to prevent lateral or rotary movement one on the other, and devices for locking the two parts together, detachably, while in use, as shown and described.

2. The combination, with a lift-cutting die having notches in its upper edge and slots as described, of a detachable die-head or anvil having a cruciform base whose arms are adapted to fit in the said notches, and catches adapted to lock the parts together, substantially as shown and described.

3. The combination, with a lift-cutting die having notches in its upper edge, of a die-head or anvil attachment having a central vertical portion and a cruciform base, which attachment receives the blows of a mallet, and retractable spring-catches adapted to lock the two parts together, the said catches and means 110 for retracting them being arranged in opposite arms of the cruciform base, substantially as shown and described.

4. The combination, with a lift-cutting die, a holder therefor, and a die-head secured 120 thereto and provided with a central bore adapted to receive and guide a nail, of the nail-driving device comprising an elongated hammer or rod adapted to work in said bore, a head constituting the anvil of said device 125 and to which the said rod is rigidly secured, and guides attached to said head and working in connection with the die-head, substantially as shown and described.

5. The combination, with a lift-cutting die, 130 a holder therefor, and a die-head secured to the die, of a nail-driving device comprising a suitable head or anvil, a nail hammer or rod adapted to work in a bore of the die-head, and

an elastic block applied to the under side of said anvil and adapted to come in contact with the die-head when the nail-driver is forced down, substantially as shown and described.

6. The combination, with a lift-cutting die, and a holder therefor, upon which the die is duly supported, of a die-head having piercing-points that serve as pick-ups for the several lifts cut by the die, and also a series of vertical guideways, of a lift-ejecting device comprising a series of pendent bars adapted to work in the said guideways, and a driving-head or anvil to which the said bars are attached, substantially as shown and described.

7. The combination, with a heel-lift-cutting die, a holder and support therefor, and a support for the lifts arranged below the die, of a die-head having piercing-points adapted to pick up the several lifts cut by the die, and having also a series of vertical guideways and a central bore for receiving a nail, by which the lifts are to be secured together, and the nail-driving and lift-ejecting device 25 consisting of an anvil or driving-head, an elongated hammer adapted to work in the bore of the die-head, and force the nail downward, and a series of pendent bars which work in the aforesaid guideways and serving 30 by contact with the lifts to force them off the piercing-points immediately following the nail-clenching operation, as shown and described.

8. The combination, with a suitable frame 35 having a sliding plate provided with an anvil on its upper side, and a die-holder arranged above said plate when the latter is in its normal position, a lift-cutting die adapted for

support within said holder, a die-head secured to said die, and provided with vertical 40 guideways, and pendent piercing-points that serve as pick-ups for the lifts cut by the die, and a device for driving and clenching a nail and subsequently ejecting the lifts, which comprises a hammer-rod adapted to work in 45 a guide in the die-head, a series of pendent bars that are also guided in said die-head and serve as ejectors for the lifts, and an anvil or driving-head to which said hammer-rod and bars are attached, as shown and described. 50

9. The combination with a lift-cutting die and holder therefor, and a lift-ejecting attachment for said die, of a slidable plate arranged in guideways, and means for holding it in normal position beneath the die as required 55 for supporting the lifts when a nail is being driven, and means for retracting said plate as required when the lifts are to be ejected from the die, as shown and described.

10. The combination with a frame having 60 an opening vertically therein, and suitable horizontal guideways, a die-holder arranged above said opening, and a die supported in said holder, of a slidable plate working in said guideways, and a means for holding it 65 normally in position beneath the die, and means for driving a nail into lifts held in the die, and means for ejecting the lifts subsequent to the nailing operation and the retraction of the said plate, as shown and described. 70
